UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-YOKE FOR RAILWAY-CAR DRAFT-RIGGING.

1,128,356.

Specification of Letters Patent. Patented Feb. 16, 1915.

Application filed April 23, 1914. Serial No. 833,842.

To all whom it may concern:

Be it known that I, JOHN F. O'CONNOR, a citizen of the United States, residing at Chicago, in the county of Cook and State 5 of Illinois, have invented a certain new and useful Improvement in Draft-Yokes for Railway-Car Draft-Rigging, of which the following is a full, clear, concise, and exact description, reference being had to 10 the accompanying drawings, forming a part of this specification.

My invention relates to improvements in draft yokes for railway car draft rigging.

The object of my invention is, to provide 15 a draft yoke of simple and strong construction.

In the drawings forming a part of this specification, Figure 1 is a plan view of a draft yoke embodying my invention; Fig. 20 2 is a side elevation partly in vertical longitudinal section on line 2—2 of Fig. 1; Fig. 3 is a cross section along line 3—3 of Fig. 2; Fig. 4 is a vertical longitudinal section on line 4—4 of Fig. 3.

25 In the drawings, I have illustrated a type of yoke generally known as a horizontal yoke, having a U-shaped yoke strap 5, consisting of the limbs 6—6 and the rear connecting member 7. Each limb 6 at its free

end is provided with a sleeve 8, each sleeve 30 preferably comprising the spaced-apart upright portions 9—9 between which the yoke limb is received, the upper and lower connecting portions 10—10, and the inner shoulder 11. The sleeves 8 are each provided with a transverse slot 12 to receive the coupler key 13, which passes through said slots and through the slot 14 of the draw-bar 15, only the rear end of the draw-bar being shown in the drawings. The 35 sleeves 8 are each suitably secured to their appropriate yoke limb by suitable means, preferably the rivets 16—16 passing through the sleeve and through the inclosed limb of the yoke. Thus each sleeve forms a band 40 surrounding one of the free ends of the yoke strap.

I claim:—

In a draft rigging for railway cars a 50 yoke consisting of a U-shaped yoke strap and a pair of sleeves, each sleeve comprising a band surrounding a free end of the yoke strap, the said bands being slotted for the passage of a coupler key therethrough.

JOHN F. O'CONNOR.
